UNITED STATES PATENT OFFICE.

JAMES C. NAUGHTON, OF ROCHESTER, NEW YORK.

KEY-RING SUPPORT.

1,191,215.

Specification of Letters Patent. Patented July 18, 1916.

Application filed March 17, 1916. Serial No. 84,839.

To all whom it may concern:

Be it known that I, JAMES C. NAUGHTON, a citizen of the United States, residing at Rochester, in the county of Monroe and 5 State of New York, have invented certain new and useful Improvements in Key-Ring Supports; and I do hereby declare the following to be a full, clear, and exact description of the invention, such as will enable 10 others skilled in the art to which it appertains to make and use the same.

My invention relates to article holders or devices for detachably clasping, fastening or holding articles which are to be carried 15 about on the clothing of a user.

More particularly stated, my invention relates to holders for key-rings and keys, comprising a novel construction, combination and arrangement of resilient body and 20 flexible sheath members, designed and adapted to be clipped on to the waist-band of a pair of trousers, or other garments, and to constitute a support for key-rings and keys, as also a sheath for such rings and 25 keys when so supported.

This invention, therefore, has for an object the production of devices of the character indicated, which are at once simple and cheap of construction, easily applied 30 and eminently satisfactory in their practical use and operation.

A further object is that of detachably locating a key-ring and keys with reference to the person of a user, so that they shall 35 at all times be most accessible and convenient for instant use.

A further object of the present invention is to obviate the serious wear and tear to which pockets are subjected by key-rings 40 and keys when carried therein.

A further object of the invention is to so sheath a key-ring and keys by means of tough, flexible and pliable guards or flaps, as to positively prevent contact with adjacent 45 articles of wearing apparel, and consequently to prevent chafing or abrading the same.

With these and other objects and advantages in view, the present invention will 50 be hereinafter particularly described and then set forth in the appended claims.

In the accompanying drawings which form part of this application for Letters Patent, and whereon corresponding numerals refer to like parts in the several views: Figure 1 is a perspective view of

the invention, showing same applied and in position for use upon the waist-band of a pair of trousers. Fig. 2 is a relatively enlarged elevation of the invention detached, 60 one corner being broken away showing frame of the holder. Fig. 3 is a perspective view of the unitary frame member of resilient material, and Fig. 4 is a vertical, and substantially central, section of the invention taken on the line 4-4 of Fig. 2.

Reference being had to the drawings and numerals thereon, 1 indicates the metallic frame or body of the structure, preferably of resilient or spring material, and of unitary construction. The horizontal portion of the said supporting frame 1 may be curved slightly as shown the better to conform to the body of a wearer, and is provided at opposite ends with integral and 75 upwardly extending spring fastening clips 2, 2, for purposes which will later appear. Projecting centrally in an opposite or downward direction, from the horizontal member of said frame 1, is a supporting 80 hook 3 which is adapted to receive and detachably retain a key-ring and keys. This hook member 3 is also by preference of integral formation, and is slightly curved as at 4 to facilitate its application to the person of a wearer, and its use.

Suspended from the horizontal member of supporting frame 1 is a tough, flexible sheath, preferably of leather, the two flaps or sides 5 and 6 thereof being folded upon 90 themselves, and upon opposite sides of the depending ring-hook 3, as best shown by Fig. 4. At its opposite upper corners the said sheath is perforated as at 7, 7 to permit passage therethrough of clips 2, 2, as 95 best shown by Fig. 2, and by this figure it is also apparent that the flaps 5 and 6 differ slightly in length.

The construction of my invention being substantially as shown and described, its 100 use and operation are so apparent that a description thereof hardly seems necessary. It may be noted, however, that the peculiarly balanced arrangement of duplicate resilient clips 2, 2, insures satisfactory attachment to a waistband, and permits of horizontal adjustment in either direction to the position of greatest convenience. It may also be noted that the unequal length of the shield flaps 5 and 6 facilitates lifting the 110 former or separating the two when removing or replacing a key-ring upon hook 3.

The foregoing being a description of my invention in its best form of construction at present known to me, it should be understood that various changes in the form, proportion and arrangement of parts may be made and substituted for those shown without materially departing from the spirit of my invention, and to all such modifications and adaptations I lay claim the same as if herein set forth and described. It should be noted also that the single unitary structure shown by Fig. 3 of the drawings is a thoroughly practical and operative device of the character set forth, and is in itself a simplified form of the present invention.

Having thus described my invention, what I now claim and desire to secure by Letters Patent is:

1. An article holder comprising in combination an integral body member of flat form the longitudinal axis of which when in operative position extends in a horizontal direction and is provided with downturned hook portions extending to one side of said body member, and an intermediate upturned supporting hook for detachably receiving the article to be supported extending wholly from the opposite side of said body member.
2. An article holder comprising in combination an integral body member of flat form the longitudinal axis of which when in operative position extends in a horizontal direction and is provided with oppo-

sitely disposed attaching hooks at the ends thereof the latter extending to one side of said body member, and an intermediate hook for detachably receiving the article to be supported extending wholly from the opposite side of said body member.

3. An article holder comprising in combination a cambered body member the longitudinal axis of which when in operative position extends in a horizontal direction and is provided with suitable attaching clips near the ends thereof, an intermediate supporting hook for detachably receiving the article to be supported, and a flexible sheath suspended from said body member upon both sides of said supporting hook.

4. An article holder comprising in combination a cambered body member the longitudinal axis of which when in operative position extends in a horizontal direction and is provided with suitable attaching clips near the ends thereof, an intermediate supporting hook for detachably receiving the article to be supported, and a flexible sheath formed of front and back flaps of unequal length suspended from said body member upon opposite sides of the said supporting hook.

In testimony whereof I affix my signature, in presence of two subscribing witnesses.

JAMES C. NAUGHTON.
